Specification for Design.

Patented Nov. 2, 1920.

Application filed December 1, 1919. Serial No. 341,819. Term of patent 7 years.

To all whom it may concern:

Be it known that I, ROY C. CASHNER, a citizen of the United States, residing at Kansas City, in the county of Jackson and State of Missouri, have invented a new, original, and ornamental Design for a Toy Vehicle, of which the following is a specification, reference being had to the accompanying drawing, forming part thereof.

The figure is a side elevational view of a toy vehicle, showing my new design.

The design consists of the body portion 1 of an animal having a forward extension 2, representing the forward legs and feet, and

a rear extension 3, representing the rear legs and feet, and at the rear of the extension 3 are disks 4 and 5. The forward part of the body 1 is also formed with a head 6 and depending from the body portion is a part 7, supporting a disk 8, the part 7 being suspended from a bar 9 having a cross piece 10 thereon and on the top of the body 1 is a flat member 11.

I claim:

The ornamental design for a toy vehicle, as shown and described.

ROY C. CASHNER.
